UNITED STATES PATENT OFFICE.

CHARLES SHAW, OF BROOKLYN, NEW YORK.

APPARATUS FOR TEMPERING SOLE LEATHER.

Application filed August 24, 1926. Serial No. 131,282.

This invention relates to apparatuses for tempering leather stock such as sole leather blanks or pieces.

Generally stated, the principal object of the present invention is the provision of an apparatus for moistening, or as it is termed in the trade, for tempering leather stock, such as is used for producing shoe soles, in a more thorough manner, and in which the stock in the form of blanks or pieces will be held separated in obtaining the result looked for.

More specifically stated, the object of the invention is the provision of an apparatus with which the leather stock will be submerged in water for a predetermined period, for thirty minutes for instance, which constitutes the soaking operation, after which the water is removed so that the leather stock will remain for a predetermined period, about twenty-four hours, enclosed and shut off from circulating air to obtain a complete saturation of the stock, which will complete the tempering process.

The nature of the invention and its distinguishing features and advantages will appear when the following specification is read in connection with the accompanying drawing, in which—

Figure 1 is a perspective view of the apparatus embodying the features of the present invention.

Fig. 2 is a vertical sectional view through the apparatus.

Fig. 3 is a perspective view of one of the trays used for supporting the leather stock to be tempered.

Referring now more particularly to the several views of the drawing, it will be apparent that, the apparatus includes a box or casing 10 of any preferred size and construction, and made from any preferred material, preferably metal. The casing is provided with supporting legs 11. The casing 10 in the present instance is of oblong shape, and is provided in the front wall thereof with an opening 12 which is closed by a hinged door 13. The opening 12 is bordered by a suitable gasket 14 of rubber or other suitable material, whereas, the inside of the door 13 is provided with a rectangular channel 15 having arranged therein a gasket 16 similarly to the gasket 14. The gaskets 14 and 16 in the channel 15 constitute a means for effectually sealing the opening 12, to provide an air and water-tight closure. The door 13 is releasably held in a closed position by suitable co-

acting latching devices 17 and 18 respectively on the door and front wall of the casing 10. The walls of the casing 10 and the door 13 provide a chamber 19. Communicating with the chamber 19 by virtue of an opening O in the bottom wall of the casing is a suitable connection 20 which serves both as an inlet and outlet for the water used in the soaking operation. A water inlet pipe 21 leads to the connection 20 as at 22 and is in communication therewith so that water flowing through the pipe 21 will enter the connection 20 and pass through the opening O into the chamber 19. The pipe 21 has connected therein a suitable cut-off valve 23. A water outlet pipe 24 is provided and leads to the connection 20 in communication therewith. The outlet pipe 24 serves for draining the water from the chamber 19. The outlet pipe 24 has connected therein a suitable stop valve 25. A by-pass 26 is provided and one end thereof is in communication with the top of the chamber 19 as at 27, and the lower end of the by-pass is in communication with the outlet pipe 24 below the valve 25 as at 28. The by-pass 26 serves as an overflow for an over-abundance of water, and also allows the air which was in the chamber 19 to be liberated therefrom as the chamber 19 is being filled with water.

In order to properly support the leather stock such as sole leather blanks from which outer soles are produced, or soles already cut, there is provided a means for supporting the blanks or soles in a separated condition, or in other words, in a spaced relationship. The said means is capable of being placed into the chamber 19 and removed therefrom. In the present instance the said means consists of a plurality of similar trays 29 adapted to be arranged in a stacked or superposed relationship. Each tray 29 comprises a box-like structure 30 comprising sides 31, ends 32 and a bottom 33. The bottom 33 is inclined with respect to the sides 31. One side 31 has the lower edge thereof spaced from the bottom 33 to provide an elongated drain opening 34. The bottom 33 is also provided with a number of drain holes 35. Arranged within the structure 30 there is a plurality of supporting members 36 arranged in spaced relationship with respect to each other, and in the present instance said supporting members are carried by the bottom 33. Each of the members 36 is bowed and has the opposite ends

thereof secured to the bottom 33. Obviously any other arrangement of supporting members 36 may be provided for the intended purpose. One of the sides 31 and 5 each of the ends 32 of the structure 30 have formed thereon an upstanding portion or flange 37 so that when a number of the trays 29 are stacked they will be held against shifting relatively endwise and sidewise in 10 one direction, and will facilitate their being stacked in alignment. Each of the trays 29 is therefore adapted to support a multiplicity of shoe leather blanks or other stock in a separated condition.

15 The tempering process is carried out in a manner presently to be described. The desired number of trays 29 have therein the leather stock which is arranged within the chamber 19, after which the door 13 is 20 closed. Water is then admitted to the chamber 19 through the inlet pipe 21, by opening the valve 23. At this time the valve 25 will be closed. The water passes from the pipe 21 into the connection 20, through the opening O into the chamber 19. Sufficient water is introduced into the chamber 19 to completely fill the same which will exclude all of the air therein. The leather stock will thus be submerged, with all of the surfaces thereof susceptible to the soaking action of the water. The leather stock is allowed to remain submerged for a period of thirty minutes, after which the water is drained from the chamber 19. This is accomplished by closing the valve 23, and by opening the valve 25. The water under the action of gravity draws the air in the bypass 26 into the chamber 19 at the top, and the water flows out of the outlet pipe 24. 30 The chamber 19 will then be substantially evacuated of water. By allowing the leather stock to remain in this condition for a period of twenty-four hours, the stock will be thoroughly moistened or saturated, which 35 completes the tempering process.

40 By providing the type of trays 29 illustrated and described, the water is allowed to freely circulate in and about the leather

55 stock while the chamber 19 is being filled, and the water in the draining operation will 50 be allowed to drain completely out of the trays 29. A suitable gage 38 is connected in communication with the chamber 19 so that the amount of water in the chamber may be seen at a glance.

55 It is to be understood that the invention is not restricted to the precise arrangement of parts shown and described, as details of construction may be modified and rearranged without departing from the spirit 60 of the invention, the scope of which is limited only by the terms of the appended claims.

I claim:

1. Apparatus for tempering shoe sole 65 leather pieces comprising a casing having a chamber and a water and air-tight door; means in said chamber adapted to support a multiplicity of the leather pieces in spaced relationship, a valved water inlet, a valved water outlet, a connection establishing communication between said chamber and said inlet and outlet, and a by-pass in communication with the top of the chamber and said outlet below its valve. 75

2. In an apparatus for tempering shoe sole leather pieces, a casing having a chamber in which the leather pieces may be placed, means for introducing water into said chamber, means for liberating the air in the chamber 80 while the water is being introduced, and means for draining the water from said chamber so that the chamber will be substantially evacuated of water.

3. In an apparatus for tempering leather 85 stock, a casing having a chamber in which the leather stock may be placed, means in the chamber adapted to support the leather stock, means for introducing water into said chamber, means for liberating the air in the chamber while the water is being introduced, and means for draining the water from said chamber so that the chamber will be substantially evacuated of water. 90

CHARLES SHAW.
